BRASSIERE

Larry L. Krieger, Dover, Del., assignor to International Latex Corporation, Dover, Del., a corporation of Delaware

Application January 20, 1955, Serial No. 34,109

Term of patent 14 years

(Cl. D20—4)

The figure is a perspective view of a brassiere in extended position showing my new design.

The S-shaped figures on the opaque breast pockets constitute decorative stitching, while the mesh fabric insert between and above the pockets is of a transparent nature.

I claim:

The ornamental design for a brassiere, as shown and described.
